(57) **CLAIM**

The ornamental design for a bottle, as shown and described.

DESCRIPTION

FIG. 1 is a perspective view of a bottle showing our new design;

FIG. 2 is a front view of the bottle depicted in FIG. 1, the opposite side being identical;

FIG. 3 is a side view of the bottle depicted in FIG. 2, representing a partial rotation of the bottle about its vertical center axis from the front view depicted in FIG. 2, the opposite side being identical;

FIG. 4 is a top view of the bottle depicted in FIG. 2;

FIG. 5 is a bottom view of the bottle depicted in FIG. 2;

FIG. 6 is a perspective view of a second embodiment of a bottle as depicted in FIG. 1;

FIG. 7 is a front view of the bottle depicted in FIG. 6, the opposite side being identical;

FIG. 8 is a side view of the bottle depicted in FIG. 7, representing a partial rotation of the bottle about its vertical center axis from the front view depicted in FIG. 7, the opposite side being identical;

FIG. 9 is a top view of the bottle depicted in FIG. 7;

FIG. 10 is a bottom view of the bottle depicted in FIG. 7;

FIG. 11 is a perspective view of a third embodiment of a bottle as depicted in FIG. 1;

FIG. 12 is a front view of the bottle depicted in FIG. 11, the opposite side being identical;

FIG. 13 is a side view of the bottle depicted in FIG. 12, representing a partial rotation of the bottle about its vertical center axis from the front view depicted in FIG. 12, the opposite side being identical;

FIG. 14 is a top view of the bottle depicted in FIG. 12;

FIG. 15 is a bottom view of the bottle depicted in FIG. 12;

FIG. 16 is a perspective view of a fourth embodiment of a bottle as depicted in FIG. 1;

FIG. 17 is a front view of the bottle depicted in FIG. 16, the opposite side being identical;

FIG. 18 is a side view of the bottle depicted in FIG. 17, representing a partial rotation of the bottle about its vertical center axis from the front view depicted in FIG. 17, the opposite side being identical;

FIG. 19 is a top view of the bottle depicted in FIG. 17;

FIG. 20 is a bottom view of the bottle depicted in FIG. 17;
 FIG. 21 is a perspective view of a fifth embodiment of a bottle as depicted in FIG. 1;
 FIG. 22 is a front view of the bottle depicted in FIG. 21, the opposite side being identical;
 FIG. 23 is a side view of the bottle depicted in FIG. 22, representing a partial rotation of the bottle about its vertical center axis from the front view depicted in FIG. 22, the opposite side being identical;
 FIG. 24 is a top view of the bottle depicted in FIG. 22; and,
 FIG. 25 is a bottom view of the bottle depicted in FIG. 22. The broken line environmental showing is for illustrative purposes only and does not form part of the claimed design.

1 Claim, 10 Drawing Sheets
